CONTAINER AND PACKAGE

George James Datz, East Rockaway, N. Y., assignor to Pepsi-Cola Company, Long Island City, N. Y., a corporation of Delaware

Application July 12, 1941, Serial No. 402,086

3 Claims. (Cl. 224—45)

This invention relates to bottle carriers, containers and packages of the type suitable for use by consumers for carrying from store to home a small number of beverage bottles, six being the customary number. Carriers of this type which have been most successful commercially have been constructed of cardboard or similar material, and are lacking in firmness and durability, their handles being too thin for comfortable use.

A general purpose of this invention is to provide a carrier, container and package of the indicated type that will be within the commercially practicable limits of cost, but which is constructed of stronger, stiffer material than the cardboard in general use. A feature of the invention is the provision of a novel handle structure especially adapted for construction from such relatively stiff, thicker material which is stronger and more comfortable to use than the handles made of cardboard or the like. A further feature is the provision of a handle made of said stiff material that can be shifted into non-projecting position within the body of the container and between the bottles to facilitate vertical stacking of the containers or packages, but which is readily lifted into projecting carrying position.

Another object of the invention is to provide a container and a package construction which will facilitate the packing and stacking of such containers or packages both horizontally and vertically without wasting space and in exactly the same space for a given number of containers or packages. The type of carrier heretofore in general use is made of relative flexible material which conforms to the dimensions of the bottles; but as the diameters of the bottles may vary considerably in practice, the resulting variation in transverse dimensions of a number of packages arranged side by side is quite substantial. With the constructions disclosed herein the containers or packages will always fit accurately into a carton or other packing receptacle constructed for them.

Another feature is the provision of an arrangement in which either the packages or the empty containers can be stacked efficiently in vertical series or tiers. In the preferred form the containers are constructed and arranged so that when they are filled with bottles to form packages and are stacked vertically, the weight of superposed packages rests on the bottles. Another specific feature is the provision of a container structure of the indicated type which facilitates stacking of the empty containers vertically in substantially less space than that required when the containers are filled, an important factor

when the containers are made of stiff material and are not collapsible.

Other objects are to provide a carrier or container construction that can be readily packed and emptied in the plant or the home, and which is convenient to handle when containing less than the full quota of bottles. The invention also includes the provision of a container construction which is adapted to be readily manufactured from standard sheet material and which can be shipped knocked down, being readily assembled at the point of use.

Other objects and advantages will appear from the following description considered in connection with the accompanying drawings in which

Fig. 1 is a side view, partly in section, of a package containing six bottles with the handle member in retracted position, its upper operative position being indicated by broken lines;

Fig. 2 is an end view, in section on the line 2—2 of Fig. 1, of the package with the handle member similarly shown;

Fig. 3 is an end view similar to Fig. 2 showing a modified form;

Fig. 4 is a fragmentary vertical section on line 4—4 of Fig. 3; and

Fig. 5 is a detail section through the handle member guide construction on line 5—5 of Fig. 4.

The invention is illustrated in a carrier designed to hold six bottles, though the same construction may be employed for carriers accommodating any even number of bottles. The carrier comprises a body 10 including ends 11, sides 12 and bottom 13 is formed of material sufficiently stiff to retain substantially the same contour during use. Such material may be wood, fiberboard, vulcanized fiber, pressed or laminated wood, or any of the various plastic materials or combinations thereof which are available or suitable for production in sheet form. The carrier may also be made of metal, or of various combinations of different materials. Its parts should, however, have sufficient thickness to provide the necessary strength and rigidity.

In the form illustrated in Figs. 1 and 2, the bottom 13 is composed of strips 14 overlapping the lower edges of ends 11 and sides 12 and slightly spaced adjacent the center of the carrier as at 15. The sides 12 overlap ends 11, and the overlapping body elements are suitably attached to each other as by nails 16 extending into the ends 11. With this construction, ends 11 may be made of wood or other material into which the nails may be effectively driven, while sides 12 and bottom 13 may be of fiberboard, pressed wood or

other stiff sheet material substantially thinner than the ends 11. Various other methods of joining the body ends, sides and bottom may be employed, but in any event it is desirable to connect the body parts at points appropriately spaced and distributed to provide a rigid body construction which will not be readily racked or distorted.

The carrier is provided with a handle member 17 vertically slidable on ends 11 between upper carrying position and lower retracted position. In the lower position member 17 does not project above the upper margins of the bottles 18 in the carrier, and in upper position extends above the bottles for a distance sufficient for convenient grasping and use of the member in carrying the container when the bottles are in place.

For this purpose member 17 is advantageously mounted in vertical guideways in ends 11 provided with suitable stops to limit the movement of the member in upper and lower positions. In the form illustrated these guideways consist of vertical slots 19 in ends 11 slidably fitting guide tongues 20 integral with member 17. The outer ends of tongues 20 are flush with the outer faces of body ends 11, and the tongues 20 extend vertically for a distance sufficient to prevent any material lateral movement of the upper margin of member 17. The ends of slots 19 serve as stops engaged by the registering upper and lower faces of tongues 20 to arrest the member 17 in the proper upper position for carrying, and in lower position suitable for stacking. In the form shown the lower faces of tongues 20 are flush with the bottom of member 17.

The body 10 is dimensioned so that the bodies 21 of bottles 18 will fit fairly snugly against each other and the adjacent portions of the body, both transversely between sides 12 and longitudinally between ends 11, forming a firm package. With this construction the handle member 17 when in lower retracted position will be located in the space between the necks 22 of the rows of bottles at opposite sides of the carrier, the illustrated embodiment being proportioned so that the lower edge of member 17 barely clears the adjacent portions of bottle necks 22. This illustration, however, is not intended to be restrictive, since the invention includes an arrangement in which the lower portion of member 17 extends into contact with or between said rows of bottles, serving in lowermost position to assist in holding the bottles in place.

Handle member 17 is provided with a finger opening 23 extending horizontally for a distance sufficient to accommodate the fingers. Opening 23 is spaced from the upper edge of handle member 17 by a distance sufficient to provide a strong rigid handle, and overlaps the spaces at each side of the neck 22 of the central bottle, providing finger space for the user which facilitates insertion of fingers in opening 23 when the member 17 is in lower position and the container is filled with bottles, the movement of member 17 into upper carrying position being part of the normal procedure of the user in picking up the carrier. The clearance between tongues 20 and slots 19 is advantageously sufficient to permit member 17 to drop of its own weight into retracted position when the carrier has been set down and the member 17 released by the user.

The construction as described is adapted for vertical stacking with the superposed container resting on either the upper margins of body ends 11 (and on the upper margin of handle member 17 if desired) or upon the upper ends of bottles

18. The latter arrangement has been found to be advantageous, and the upper margins of ends 11 and handle member 17 are, therefore, located slightly below the level of the tops of bottles 18. 5 Said upper margins of ends 11 may, however, be provided with a flat portion 24 of sufficient extent to support a superposed container when no bottles are in the lower container.

The upper side portions of the ends 11 are advantageously cut away to expose the outer portion of the upper parts of bottles 18. In the form illustrated this arrangement includes the provision of opposed sloping margins 25 extending from the ends of the flat top margin 24 to flat side margins 26 of ends 11. The body sides 12 advantageously extend to the tops of side margins 26, or at least not above such tops, at points sufficiently high on the bottle bodies 21 to hold the bottles securely in position. In the form shown sides 12 and side margins 26 extend substantially to the top of the bottle bodies 21. If desired, sides 12 may be apertured to expose the labels or other portions of the bottle bodies.

In the modified construction illustrated in Figs. 3, 4 and 5 reinforcing straps 30 which may be of thin metal readily bent to the desired shape and readily pierced by nails 16 extend across bottom 13 and sides 12 in register with ends 11, the nails 16 passing through straps 30, which may terminate about half way up the sides 12 as shown. One nail 16 may be positioned to hold each strap 30 against the bottom of the adjacent end 11 in the space 15. In this construction the sides 12 may be provided with inwardly beveled 35 upper edges 31.

The handle member 37 is similar in construction, location and operation to handle member 17, differing principally in the supporting and guiding construction. For this purpose a guide member 38 is provided at each side of member 37, advantageously constructed of relatively thin sheet metal readily bent to the desired shape, mounted on member 37 in register with guide tongue 20 and having a portion engaging the outer face of the adjacent end 11 to prevent end-wise movement of said tongue in its slot 19. The specific form of guide member illustrated consists of a flat head 39 lying against the outer face of tongue 20 and extending inwardly at each side 45 of the tongue beyond the adjacent end 11. An inturned flange 40 at each side of head 39 lies against the inner face of the head and connects it with a face plate 41 which lies against the side face of tongue 20 and extends inwardly along 50 the surface of handle member 37, to which it is attached by suitable means. In the form shown such means includes a retaining tongue 42 struck from each face plate 41 and forced into the material of member 37 (Fig. 5), each tongue 42 extending toward head 39. Further retaining elements may also be provided, such as pointed retaining projections 43 located above and below each tongue 42 and likewise forced inwardly into the material of handle member 37.

65 The various parts of guide member 38 may readily be formed from a single piece of standard sheet metal by simple operations, and the members 38 may be readily placed in position over tongues 20 after the latter have been inserted 70 in slots 19, the guide members being permanently and solidly fixed in place on handle member 37 by a simple stamping operation which forces tongues 42 and projections 43 into the material of the handle member.

75 To avoid the projections of the guide member

head 39 beyond ends 11, suitable recesses 44 may be provided in the outer faces of ends 11 at either side of slots 19, into which the lateral projecting portions of guide member heads 39 extend with flanges 40 slidably engaging the inner faces of the recesses 44 and with the outer faces of heads 39 flush with or inset from the outer faces of ends 11.

In this form the lower margin of handle member 37 extends downwardly into register with the bodies 21 of bottles 18, being positioned between the bodies of the two rows of bottles and serving to hold the bottles in place, with the bottles of one row out of contact with the bottles of the other row. For this purpose the lower margin of member 37 is shown as extending below tongues 20, though this showing is not intended to be restrictive.

The disclosed type of construction provides a particularly neat and attractive package in which the upper portions of the bottles are visible and accessible, although the bottles are securely held in place. It also provides economy of material and simplicity in cutting. Moreover, it permits ready stacking of the empty containers with economy of space. When a row of containers is placed with sides 12 contacting and in register, a second row may be stacked thereon by inverting the containers of such row and placing them between the containers of the first row with the sloping margins 25 resting on each other. Additional pairs of tiers may be similarly superposed.

This construction also provides adequate material around guide slots 19, the upper ends of which are advantageously spaced about equally from the top margins 24 and sloping margins 25, to provide the required strength and rigidity.

The container constructed in the indicated manner is strong, light and convenient to use. The bottles may be readily and rapidly inserted and removed. In the form illustrated in Figs. 1 and 2 the distance between the top of each side 12 and the lower margin of the handle member 17 in retracted position is advantageously greater than the width of a bottle body 21 to facilitate insertion of the first row of bottles and removal of the last row. The second row can be inserted by lifting handle member 17 if necessary, though the parts can be proportioned so that this is not necessary. Moreover, if the member 17 tends to obstruct the withdrawal of a bottle it will automatically be lifted by such withdrawal until it is free of the bottle. In the form shown in Figs. 3, 4 and 5 the handle member 37 can likewise be lifted to facilitate insertion or removal of the bottles 18, though normally this is not necessary since the bottles are free for vertical movement when handle member 37 is in lower position.

While a construction has been described which is assembled from a plurality of flat elements, and such an arrangement has many advantages, the disclosure is not intended to be restrictive, since contiguous portions of the body 10, or

even the entire body, are adapted to be formed either from a single sheet of material which is appropriately bent or otherwise shaped to the desired contour, or from plastics or other deformable or moldable materials which may be cast, pressed or otherwise shaped into the desired form. Likewise, although the handle member 17 has been disclosed in the form of an integral sheet of material provided with a finger opening, this disclosure is not intended to restrict the invention, either as to the form of the handle or the particular arrangement for mounting it slidably on the body 10.

I have described what I believe to be the best embodiments of my invention. I do not wish, however, to be confined to the embodiments shown, but what I desire to cover by Letters Patent is set forth in the appended claims.

I claim:

20. 1. A container comprising a body forming a compartment open at the top and having substantially rigid opposed ends provided with registering guideway slots, and a handle member slidably mounted in the slots including a retaining member extending through a slot and slidably engaging an outer face portion of the contiguous end, said contiguous end being formed of a single sheet of relatively thick material and including recesses extending outwardly from the opposite sides of the slot, said retaining member being provided with laterally projecting end engaging elements fitting said recesses and located entirely within the plane of the outer face of said contiguous end.
25. 2. A container for two parallel rows of bottles comprising substantially rigid bottom, side and end walls of sheet material forming a compartment open at the top, the end walls of the compartment extending above the side walls and being reduced in width above the tops of the side walls to facilitate access to the bottles in the compartment, said end walls having registering vertical guide slots in the reduced portions of said end walls, and a sliding handle member having
30. 45. a body of sheet material formed with a finger hole and provided with a tongue rigid with and projecting from each end of said body, each of said tongues extending with a slide fit in a respective guide slot and each of said tongues having an upper surface contacting a complementary surface in the upper end of each said slot to thereby support the container and its contents, the length of said slots being sufficient to permit said handle member to extend above the tops of the bottles in position for grasping in upper position and below the tops and between the rows of the bottles when in lower position.
35. 50. 55. 3. A container as set forth in claim 2, wherein upper margins of the end walls are provided with a flat portion of sufficient extent to support a superposed container when no bottles are in the lower container or when the height of the bottles in the lower container is less than that of the end walls.
60. 65. GEORGE JAMES DATZ.
